UNITED STATES PATENT OFFICE

105,018

DESIGN FOR A DRESS

Concetta Jaccarino, New York, N. Y.

Application April 5, 1937, Serial No. 68,552

Term of patent 3½ years

To all whom it may concern:

Be it known that I, Concetta Jaccarino, a citizen of the United States, residing in the city and State of New York have invented a new, original, and ornamental Design for a Dress, of which the following is a specification, reference being had to the accompanying drawing, constituting a part thereof.

I claim:

The ornamental design for a dress, substantially as shown. CONCETTA JACCARINO.
